UNITED STATES PATENT OFFICE.

THOMAS E. RAGLAND, OF ATLANTA, GEORGIA.

DESIGN FOR A BARREL-COVER.

No. 39,058.

Specification for Design.

Patented Feb. 4, 1908.

Application filed November 20, 1907. Serial No. 403,089. Term of patent 14 years.

To all whom it may concern:

Be it known that I, THOMAS E. RAGLAND, a citizen of the United States, residing at Atlanta, in the county of Fulton and State of Georgia, have invented a new, original, and ornamental Design for Barrel-Covers, of which the following is a specification, reference being had to the accompanying drawings, forming part of this specification, in which:

The figure is a perspective view of a barrel cover, showing my new design.

I claim:

The ornamental design for a barrel cover, as shown.

THOMAS E. RAGLAND.
